UNITED STATES PATENT OFFICE.

OTTO HENNINGER, OF ST. LOUIS, MISSOURI.

DESIGN FOR A BREAD-BOARD SCRAPER OR SIMILAR ARTICLE.

Application filed November 11, 1927. Serial No. 24,076. Term of patent 8½ years.

To all whom it may concern:

Be it known that I, OTTO HENNINGER, a citizen of the United States of America, residing at the city of St. Louis, State of Missouri, have invented a new, original, and ornamental Design for Bread-Board Scraper or Similar Article, of which the following is a specification, reference being had to the accompanying drawing, forming a part thereof.

The drawing is a perspective view of a bread-board scraper or similar article embodying my new design.

I claim:

The ornamental design for a bread-board scraper or similar article as shown.

OTTO HENNINGER.
